[57] ABSTRACT

A hand operated handle which can be used for painting. The handle consists of two members; a piece of shaped plywood and a spring like wire. Both members being so arranged as to receive a detachable lambskin roller cover.

FIG. 1

FIG. 2

FIG. 3

FIG. 4

INVENTOR
MARK DESCANT
BY

PAINT APPLICATOR

SUMMARY OF THE INVENTION

A single piece of shaped plywood member to fit into a round hole 1½ inches in diameter on one end (straight end), and having a rounded handle on the opposite end. A continuous spring like wire going through a bore at the rounded end and extending to the other end of wood member, and fastened at ends on opposite sides.

BRIEF DESCRIPTION OF THE DRAWINGS

In the drawings:

FIG. 1 is a perspective view of my invention;

FIG. 2 is a side view thereof;

FIG. 3 is a detail top view of handle and wire; and

FIG. 4 is a perspective side view of my handle after lambskin roller cover is inserted onto handle, and is ready for use.

DETAILED DESCRIPTION OF PREFERRED EMBODIMENTS

Referring now to FIGS. 1-4, consisting of a shaped plywood member 10, with a rounded handle 15 on one end and handle being 3 inches high. A bore 30 is drilled through member 10 at handle end. A spring like wire 24 going through bore 30, bending and being parallel to sides of member 10 for the full length then bending around end and secured in fixed position with fasteners 18 to opposite sides of member. Wire member 24

should maintain a separation of one-half inch on each opposite side of member 10 to create pressure against inside of lambskin roller cover 16 to keep cover in an unmovable and unrollable fixed position. Member 10 is inserted into hole 29 of lambskin roller cover 16 and is ready for use. In use, while holding handle in hand and moving roller cover up and down, or in desired direction, paint is thus applied to surface of objects.

While I have described my invention with particular reference to the drawings, such is not to be considered as limiting its actual scope.

Having thus described this invention, what is asserted as new is:

1. In combination with a roller cover used in roller painting, an improved paint applicator comprising: a rigid structure having two substantially parallel legs of unequal length and a joining end portion substantially normal to and transverse said legs for holding said legs together in rigidly offset relation, the shortest of said legs of unequal length being the part for manually grasping; and a spring-like wire passing around the longest of said legs of unequal length, said wire being secured to the ends of said longest leg but flexibly offset from the sides thereof for engaging said roller cover in stationary fixed relation therewith.

2. An improved paint applicator as described in claim 1 wherein said spring-like wire passes through a hole defined in the joined end of said longest leg and is fixed to the sides adjacent the free end of said longest leg.
